UNITED STATES PATENT OFFICE.

CHARLES A. VORIES, OF LOS ANGELES, CALIFORNIA, ASSIGNOR, BY DIRECT AND MESNE ASSIGNMENTS, TO ALBERT BRUSH, OF LOS ANGELES, CALIFORNIA.

DESIGN FOR A SIGNAL-LIGHT FOR AUTOMOBILES.

55,833.

Specification for Design.

Patented July 13, 1920.

Application filed October 27, 1919. Serial No. 334,625. Term of patent 14 years.

To all whom it may concern:

Be it known that I, CHARLES A. VORIES, a citizen of the United States, residing at Los Angeles, in the county of Los Angeles and State of California, have invented a new, original, and ornamental Design for a Signal-Light for Automobiles, of which the following is a specification, reference being had to the accompanying drawing, forming a part thereof.

Figure 1, is a face view, Fig. 2 an edge view and Fig. 3 an end view of a signal

light for automobiles showing my new design.

I claim—

The design for a signal light for automobiles substantially as shown.

Signed at Los Angeles, in the county of Los Angeles and State of California, this 11th day of October, 1919.

CHAS. A. VORIES.

Witness:

JAMES R. TOWNSEND.
